United States Patent Office.

CHARLES J. HAUCK, OF BROOKLYN, NEW YORK.

Design No. 2,862, dated January 28, 1868.

DESIGN FOR AN OIL-CAN.

The Schedule referred to in these Letters Patent and making part of the same.

TO ALL WHOM IT MAY CONCERN:

Be it known that I, CHARLES J. HAUCK, of 26 and 28 Stagg street, Brooklyn, Eastern District, in the county of Kings, and in the State of New York, have invented a new Design for Oil-Fillers; and I do hereby declare that the following is a full, clear, and exact description thereof, which will enable those skilled in the art to make and use the same, reference being made to the accompanying drawing, forming part of this specification, which drawing, consisting of only one figure, shows an elevation of a filler made according to my design.

The letter A designates the upper part of a filler, the shape of which is that of a truncated cone, whose top is surmounted by the inlet-tube C. The curved handle B is placed on one side of the part A, and on the opposite side is the spout D, which is curved at its outer end, as seen at E. The air-tube F is also curved at the part G where it overlies the curved part of the spout, and the said curved part G is projected a little beyond the end of the spout, so as to produce, in conjunction with the spout, the appearance of a beak.

What I claim as new, and desire to secure by Letters Patent, is—

The design for an oil-filler as shown and described.

This specification signed by me, this 8th day of November, 1867.

C. J. HAUCK.
